UNITED STATES PATENT OFFICE.

HENRY ADLER, OF PITTSBURG, PENNSYLVANIA.

DESIGN FOR A GAS-STOVE.

SPECIFICATION forming part of Design No. 33,654, dated December 4, 1900.

Application filed October 26, 1900. Serial No. 34,511. Term of patent 14 years.

To all whom it may concern:

Be it known that I, HENRY ADLER, a resident of Pittsburgh, in the county of Allegheny and State of Pennsylvania, have invented a new and original Design for Gas-Stoves; and I do hereby declare the following to be a full, clear, and exact description thereof, referring

once being had to the accompanying drawing, in which the figure illustrates a perspective view of a gas-stove embodying my design.

The leading feature of my design consists in a gas-stove having a reflector base or bottom extending out from the body of the stove.

It also consists in a gas-stove having the shape and form, as well as the configuration and ornaments, substantially as herein shown and described.

As illustrated in the drawing, 1 represents the sides, the front 2 of which extends out at an angle to front base-plate 3, which is secured to the sides 1 and has the front legs 4 secured thereto and to the sides 1. Rear legs 5 are also secured to the sides 1 and back 6, and extending across between the sides 1 above the angular portions 2 and below the top plate 2' is the upper face-plate 7, within which are fitted the pieces 8 of colored glass.

The sides 1, top plate 2', base-plate 3, and upper face 7 are formed with the corrugations 9 therein, and said top 2' has vertical

pipes 2" opening out of the same. A curved corrugated reflector-plate 10 is secured to the base-plate 3 and extends up to the burner 11. Corrugated reflector-plates 12 are also secured on the inside of the side plates 1, in front of and adjacent to the curved reflector-plate 10.

Fitting down over the top plate 2' is the top or cover 13, which is provided with the flanges 14, extending around the same for fitting down over the sides 1, back 6, and upper face-plate 7, said cover 13 having the upwardly-curved portion 15 thereon, which is provided with a series of openings and perforations 16 therein, and a roll portion 17 is formed on the curved portion 15, on which is secured an ornamental handle 18.

What I claim as my invention, and desire to secure by Letters Patent, is—

The design for a gas-stove, substantially as herein shown and described.

In testimony whereof I have hereunto set my hand, at Pittsburgh, in the county of Allegheny and State of Pennsylvania, this 23d day of October, 1900.

HENRY ADLER.
